UNITED STATES PATENT OFFICE.

GEORGE L. WISER AND GEORGE H. WALCOTT, OF ELKHART, INDIANA.

MUSICAL WIND INSTRUMENT.

SPECIFICATION forming part of Letters Patent No. 784,608, dated March 14, 1905.

Application filed October 22, 1904. Serial No. 229,559.

To all whom it may concern:

Be it known that we, GEORGE L. WISER and GEORGE H. WALCOTT, citizens of the United States, residing at Elkhart, in the county of Elkhart and State of Indiana, have invented certain new and useful Improvements in Musical Wind Instruments; and we do hereby declare that the following is a full, clear, and exact description of the same, reference being had to the annexed drawings, making a part of this specification, and to the letters of reference marked thereon.

The present invention has relation to certain new and useful improvements in musical wind instruments, and refers more particularly to that class of instruments having valve attachments, such as "cornets-à-pistons" and similar wind instruments, and has for its object to provide means whereby the instrument is rendered in perfect tune in any key by enabling the performer to increase the length on certain tones that are naturally too sharp on the valve instruments in ordinary use.

With the improvements hereinafter described every tone may be made in perfect tune with ease and without humoring, the extra length being obtained by a simple means that will control the two distinct lengths of the instrument which is required to regulate the temperament thereof, thus obtaining perfect tune in any key.

The invention consists in the means substantially as shown in the drawings and hereinafter described and claimed.

Figure 1 of the drawings is a side elevation of one of many forms of musical wind instruments, showing our invention applied thereto, the instrument being one of the many kind having piston-valves connecting therewith; Fig. 2, a detail perspective view, on an enlarged scale, showing more clearly the mechanism for controlling the two lengths of the instrument; Fig. 3, a side elevation, partly in section, showing in full and dotted lines the adjustable length in its several positions.

In the accompanying drawings is shown one of many forms of musical wind instruments to illustrate the application of our invention thereto, the valve-cylinders being shown at A B C, in which work the valve-pistons *a b c*,

respectively, the usual tube D, which connects with the valve-cylinder C, having the mouth-piece *d*. The U-shaped tube E connects with the cylinder C, and the trumpet-shaped portion of the instrument, as indicated at F, has its tube connecting with the valve-cylinder B, and the curved tube G connects with the valve-cylinder A, a second tube H connecting with the valve-cylinders A B, and to this tube is connected the slideable and adjustable tube I, to which our invention is applied.

In describing in detail the construction of the instrument herein shown it should be understood that no claim is made thereto, as it is one of many of this class of instruments that are in common use and shown only to illustrate the application of the invention to the instrument to give a full understanding thereof.

That portion of the musical wind instrument in which the invention resides comprises the means for controlling the slideable tube I, whereby every tone may be made in perfect tune, the construction admitting of the tube being adjusted to two distinct lengths, as shown in dotted lines in Fig. 3 of the drawings.

The means employed to accomplish the above-named object consist in the two rods J K, the former having its bearing in a stationary bracket E upon the tube H, in which said rod is slideable, the rod at one end being pivotally connected to the slideable tube I, as shown at *f*, any means being employed to form this pivotal connection. The rod J extends through a bracket *g*, which is held stationary upon the rod by a suitable set-screw *h* or other preferred means, and the end of the rod is pivotally connected at *i* to the under side of a suitable key L for operating the same. The rod K has its free end loosely supported in a bearing *j*, which projects from the bracket *g*, which is held stationary upon the rod by a suitable set-screw *h*, and said rod is pivotally connected to the under side of a key M, as shown at *l*. The rod K has a bracket *m*, held thereon by a set-screw *n* or by any other suitable means found most desirable, the bracket *e* as well as the bearing *j* acting as stops to limit the movement of the rods, the rod *j* having a suitable

packing σ , of felt or other suitable material, and the brackets g m having packings p q , of similar material, so as to render the rods noiseless when operated. The brackets g and m are adjustable upon the rods by means of the set-screws hereinbefore described, whereby the extent to which the tube I may be extended is regulated and adjusted as circumstances require, the bracket acting as stops to limit the movement of the rods and the corresponding movement of the slidable tube.

The keys L M , which receive the fingers or thumbs of the player when it is desired to extend the tube I , are hinged or otherwise suitably connected to some portion of the instrument, as in the present instance to the valve-cylinder A , and the keys are rendered spring-actuated through the medium of a suitable spring, as shown at N , or by any other preferred means, so that when the keys are pressed down and the finger removed the keys will resume their normal position and draw the rods up with them and also the slidable tube. Upon the under side of the key M is a projecting finger r , which is rigid thereon so as to move with the key, so that when the key L is pressed down it will strike the finger and carry the former key with it, the finger being shown in Fig. 2 of the drawings. The keys and their connections with the slidable tube enable said tube to be increased in length on certain tones that would be naturally too sharp on the valve instruments heretofore in use, the tube being capable of adjustment by the 35 adjustable brackets or stops on the rods. The

spring-actuated keys, in connection with the rods and the slidable tube with which the rods connect, are considered of importance in controlling the slidable tube to a nicety without depending upon the hand alone.

40

Having now fully described our invention, what we claim as new, and desire to secure by Letters Patent, is—

1. In a musical wind instrument, a slidable tube, spring-actuated keys, rods pivotally connected thereto, one of said rods pivotally connected to the slidable tube, and means for adjustably connecting the rods together whereby the extent of their sliding movement with relation to each other may be adjusted and controlled, substantially as and for the purpose set forth.

45

2. In a musical wind instrument, a slidable tube, hinged and spring-actuated keys, rods pivotally connecting therewith, one of said rods being pivotally connected to the slidable tube, brackets with which the rods are adjustably connected, one of said brackets having an outwardly-extending bearing with which one of said rods engages, and a stationary 50 bracket upon the instrument to form a guide and support for one of the rods, substantially as and for the purpose described.

55

In testimony whereof we affix our signatures in presence of two witnesses.

GEORGE L. WISER.

GEORGE H. WALCOTT.
